S. P. TAYLOR,
FENDER,
APPLICATION FILED OCT. 6, 1919.

Patented May 11, 1920.

Inventor

S. P. Taylor

By Watson E. Coleman

Attorney

UNITED STATES PATENT OFFICE.

SILAS P. TAYLOR, OF LORETTO, TENNESSEE, ASSIGNOR TO TENNESSEE IMPLEMENT SALES CO., OF LORETTO, TENNESSEE, A CORPORATION OF TENNESSEE.

FENDER.

1,339,586.

Specification of Letters Patent. Patented May 11, 1920.

Application filed October 6, 1919. Serial No. 328,643.

To all whom it may concern:

Be it known that I, SILAS P. TAYLOR, a citizen of the United States, residing at Loretto, in the county of Lawrence and State of Tennessee, have invented certain new and useful Improvements in Fenders, of which the following is a specification, reference being had to the accompanying drawings.

This invention relates to certain improvements in fenders and has relation more particularly to a device of this general character especially designed and adapted for use in connection with plows or kindred earth working members, and it is an object of the invention to provide a novel and improved device of this general character which may be readily and conveniently supported in working position, and which may be adjusted in a manner to best meet with the requirements of practice.

The invention consists in the details of construction and in the combination and arrangement of the several parts of my improved fender whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in perspective of a fender constructed in accordance with an embodiment of my invention, and applied to the shank of a spring 2 or ground working member, and,

Fig. 2 is a view in perspective illustrating my improved fender as herein embodied, applied to the beam of a plow.

My improved fender, as herein disclosed, comprises a flat plate P of desired dimension, and which, when in applied position, has its flat faces substantially vertically disposed. The plate P is substantially rectangular in form and has its lower forward portion disposed on an incline, as indicated at a. The upper forward portion of the plate P is pivotally engaged, as at 1, with an intermediate portion of a depend-

ing arcuate arm 2, and the lower end portion of said arm 2 extends across a curved slot 3 disposed transversely of the plate P and concentric to the pivot 1.

Carried by the arm 2 is a headed shank 60 or member 4 extending through the slot 3, and whereby the plate P is capable of limited swinging movement about the pivot 1, and is also held in substantially a fixed line of vertical travel. Normally the plate P is 65 at the limit of its downward movement and maintains such position by gravity, however, the plate P is permitted to readily rise and fall in accordance with the irregularities in the surface over which the same 70 may travel.

The upper end portion of the arm 2 is provided with a laterally disposed extension 5 substantially perpendicularly related to the plate P, and said extension terminates in a returned portion 6 overlying the extension 5. Disposed through the inner portion of the extension 5 and the free end part of the returned portion 6 is a screw or bolt 7 with which coacts the clamping 80 nut 8, preferably having direct contact with the returned portion 6.

When my improved fender is employed in connection with a cultivator the shank of a tooth or ground working member is 85 arranged between the extension 5 and portion 6 and the arm 2 is effectively clamped thereon through the instrumentality of the coacting screw or bolt 7 and the nut 8. When the fender is applied the same 90 extends rearwardly and coacts with a side or end shank, although I do not wish to be limited to this exact arrangement.

When my improved fender is employed in connection with a plow a plate 9 is arranged between the extension 5 and portion 6 with the screw or bolt 7 disposed through said plate. The plate 9 is carried by a bracket 10, which is adapted to contact with a side face of a plow beam B.

Disposed through the bracket 10 are the screws or bolts 11 which are also directed through a plate 12 adapted to engage the opposite side face of the beam B. The clamping nuts 14 coact with the screws or 105 bolts 11 and directly contact with the plate 12, whereby the bracket 10 is effectively clamped to the beam B.

From the foregoing description, it is thought to be obvious that a fender con-

structed in accordance with my invention is particularly well adapted for use by reason of the convenience and facility with which it may be assembled and operated and it
5 will also be obvious that my invention is susceptible of some change and modification without departing from the principles and spirit thereof and for this reason I do not wish to be understood as limiting my
10 self to the precise arrangement and formation of the several parts herein shown in carrying out my invention in practice except as hereinafter claimed.

I claim:

- 15 In combination with a support for a ground working implement, an outstanding

bracket carried by the support, a plate disposed through the bracket, a fender co-acting with the ground working implement and including an upstanding arm, the 20 upper end portion of the arm being provided with a lateral extension terminating in a returned portion, said extension and returned portion straddling the plate, and means disposed through the extension of 25 the arm, the returned portion of the extension and the plate for securing the arm to the plate.

In testimony whereof I hereunto affix my signature.

SILAS P. TAYLOR.
